UNITED STATES PATENT OFFICE.

HERMAN E. GOTHLBERG, JR., OF ROSELLE PARK, NEW JERSEY.

DESIGN FOR A CANOPY-RING FOR LIGHT-FIXTURES.

41,822.

Specification for Design.

Patented Oct. 3, 1911.

Application filed March 21, 1911. Serial No. 616,034. Term of patent 7 years.

To all whom it may concern:

Be it known that I, HERMAN E. GOTHLBERG, Jr., a citizen of the United States, residing at Roselle Park, in the county of Union, State of New Jersey, have invented a new, original, and ornamental Design for a Canopy - Ring for Light - Fixtures, reference being had to the accompanying drawing, forming part thereof.

In the accompanying drawing, Figure 1 is

a plan view of a canopy ring showing my new design; and, Fig. 2 a cross section thereof on the line 2—2.

I claim;

The ornamental design for a canopy ring for light fixtures as shown.

HERMAN E. GOTHLBERG, JR.
